UNITED STATES PATENT OFFICE.

FREDERIC A. CURTIS, OF TOLEDO, OHIO, ASSIGNOR TO LUÉLLA G. BUTLER, OF
TOLEDO, OHIO.

DEFLECTOR FOR OIL-BURNERS.

1,116,874.

Specification of Letters Patent. Patented Nov. 10, 1914.

Application filed December 29, 1913. Serial No. 809,259.

To all whom it may concern:

Be it known that I, FREDERIC A. CURTIS, a citizen of the United States, and a resident of Toledo, in the county of Lucas and 5 State of Ohio, have invented a certain new and useful Deflector for Oil-Burners; and I do hereby declare the following to be a full, clear, and exact description of the invention, such as will enable others skilled 10 in the art to which it appertains to make and use the same, reference being had to the accompanying drawings, and to the characters of reference marked thereon, which form a part of this specification.

15 My invention relates to deflectors for burners of the class particularly adapted for use in connection with the burning of hydrocarbon oils of low specific gravity, such for instance, as kerosene, in lamps for 20 illuminating purposes, but is not restricted to such as it may be employed in any connection for which it may be adapted or appropriate.

The object of my invention is the provision 25 of a single piece deflector of the character described, which is simple and inexpensive in its manufacture and construction, is easily and quickly applied to a burner dome, and is so fashioned as to direct the 30 air supply to the burner flame where it is most needed, whereby a large white flame is created and the black carbon deposits on the chimney are entirely overcome or reduced to a minimum, thus enhancing the efficiency, 35 practicability and commercial value of deflectors of this nature.

The invention is fully described in the following specification, and while, in its broader aspect, it is capable of embodiment 40 in numerous forms, a preferred embodiment thereof is illustrated in the accompanying drawings, in which:—

Figure 1 is a sectional view of a burner equipped with my invention taken on the 45 dotted line $x-x$ in Fig. 2. Fig. 2 is a central vertical section on the line $y-y$ in Fig. 1, with a part of the deflector broken away. Fig. 3 is a perspective view of the deflector. Figs. 4, 5 and 6 are side, top and end views 50 thereof, respectively, and Fig. 7 is a plan of the blank from which the deflector is formed.

Referring to the drawings, 1 designates the base of a kerosene-oil burner of customary form, 2 the wick-tube rising there-

from, and 3 the burner dome, which is mounted in the usual or any suitable manner on the base 1 and has the customary flame slot or opening 4 in its top in register with the wick-tube.

60 The deflector embodying my invention is preferably stamped in a single piece from sheet-metal, and comprises the two opposing substantially semi-circular sides 5, 5, and the parts 6, 6, which latter connect the sides 65 at the ends of their top or straight edges 7. The deflector, in its blank form, resembles a circular disk having an elongated diametrically-disposed opening 8 therein, which opening has its side edges substantially 70 parallel and its end walls forming the narrow end parts 6, 6, as shown in Fig. 7.

In shaping the blank to form the deflector, the side portions 5, 5 thereof are 75 bent toward each other along the dotted lines 9 (Fig. 7) until they stand substantially in parallel planes, the distance between the sides being greater than the width of the wick-tube 2, and the end parts 6, 6 being disposed without opposite ends of 80 the tube top, as shown in Fig. 1, to permit the flame rising from the wick to pass freely upward through the deflector opening.

The deflector blank or disk is preferably 85 of substantially the same diameter as the cross-sectional area of the interior of the dome 3 at the base of the flame slot 4 therein, to permit the deflector, when mounted within the dome, to have its ends fit closely against the dome wall at the respective bases 90 of the flame slot 4 therein, so that the flame-feeding air, which rises within the dome, is prevented from passing between the outer edges of the parts 6, 6 and the dome wall. The deflector is secured within the burner 95 dome, in the present instance, by ears 10, one of which projects outward from the outer edge of each part 6 centrally thereof and through the dome slot and rests upon the respective end wall or base thereof with 100 its free end portion bent downward as shown in Figs. 1 and 2. The deflector, when mounted within the dome, has its top edge disposed above the upper end of the wick-tube, in spaced relation thereto, as shown 105 in Fig. 2.

It is found in practice that by making the bottom edges of the deflector sides 5, 5 of convexed form, or gradually restricted in depth from their central portions to the end 110

parts 6, 6, the upward flow of air through the deflector to feed the flame increases in volume outward from the center thereof so that the greatest volume envelops the end portions of the flame, where it is most needed, and effects a thorough combustion of the gases and carbon particles at such points. The efficiency of the deflector is further enhanced by notching the inner edge 10 of each part 6 at its ends, as shown at 11, so that a stream of air rises from each corner of the opening 8 and co-operates with the opposing stream to flatten and broaden the flame, and also increases the whiteness 15 and light giving quality thereof.

I wish it understood that my invention is not restricted to any particular form, construction and arrangement of the parts, except in so far as such limitations are specified in the claims, as numerous changes may 20 be made within the spirit of the invention.

Having thus described my invention, what I claim as new, and desire to secure by Letters Patent, is,—

25 1. The combination with an oil burner having a dome and a wick tube within the dome, of a deflector mounted within the dome and having opposing depending sides which are gradually restricted in depth 30 from near the centers to the ends thereof, the top portion of the deflector being above the wick tube.

35 2. The combination with an oil burner having a dome and a wick tube, of a deflector disposed within the dome and having opposing sides, the bottom edges of which substantially describe arcs of circles, the top portion of the deflector being disposed above the wick tube.

40 3. The combination with an oil burner having a dome and a wick tube, of a deflector disposed within the dome and having opposing sides, the top edges of which are substantially level and the bottom edges 45 thereof of arcuate form with the arcs terminating at their ends adjacent to the level of the top edges, the top portion of the deflector being disposed above the wick tube.

45 4. The combination with an oil burner 50 having a dome and an inclosed wick tube, of a deflector encompassing the upper portion of the wick tube in spaced relation thereto, with its top portion above the wick tube, said deflector having opposing sides, the 55 bottom and end edges of each of which are parts of a common arc.

5. The combination with an oil burner having a dome and an inclosed wick tube, of a deflector mounted within the dome with its upper portion above the wick tube, said 60 deflector having end and side portions forming a flame opening, the sides being connected by and depending from the end portions.

6. The combination with an oil burner 65 having a dome and a wick tube disposed therein, of a deflector mounted within the dome with its top portion above the wick tube and having opposing sides, and end portions connecting the sides in substantially 70 the plane of their top edges and co-operating with the sides to form a flame opening, the outer edges of the end portions being in abutment with the respective side walls of the dome.

7. The combination with an oil burner having a dome and a wick tube therein, of a deflector mounted within the dome in contact therewith at its ends above the wick tube, said deflector having opposing sides 80 with substantially straight upper edges and convexed lower edges, and end portions connecting the sides in substantially the plane of the top edges thereof.

8. A deflector of the class described, having opposing sides and end portions connecting the sides adjacent to the ends of their top edges and being notched at the ends 85 of their inner side edges.

9. A deflector forming an air and flame 90 opening and having the end walls of such opening notched at the end portions thereof.

10. A deflector blank of circular form having a diametrically disposed opening 95 therein with the end walls of such opening notched at the ends thereof.

11. A deflector blank of circular disk-like form having a diametrically disposed opening with parallel side walls and inwardly 100 protuberant end walls, and ears projecting in opposed relation from the side edge of the blank in longitudinal register with said opening.

In testimony whereof, I have hereunto 105 signed my name to this specification in the presence of two subscribing witnesses.

FREDERIC A. CURTIS.
